Des. 195,095
Patented Apr. 23, 1963

195,095

COMBINED LAMP AND PLANTER

Bela Bardos, 7604 Granada Drive, and Ronald N. Brun-ger, 7526 Granada Drive, both of Fort Wayne, Ind.

Filed Mar. 29, 1962, Ser. No. 69,495

Term of patent 14 years

(Cl. D48—31)

FIG. 1

Fig. 5

FIG. 1 is a perspective view taken from the top and one side of a combined lamp and planter, showing our new design;

FIG. 2 is a side elevational view thereof;

FIG. 3 is a front elevational view thereof;

FIG. 4 is a top plan view thereof; and

FIG. 5 is a cross-sectional view taken on the line 5—5 of FIG. 2.

We claim:
The ornamental design for combined lamp and planter, as shown.
